INVENTOR:

August Goertz,
BY Fred C. Fraenzel, ATT'Y.

UNITED STATES PATENT OFFICE.

AUGUST GOERTZ, OF NEWARK, NEW JERSEY.

PURSE-FRAME.

SPECIFICATION forming part of Letters Patent No. 453,282, dated June 2, 1891.

Application filed February 18, 1891. Serial No. 381,818. (No model.)

To all whom it may concern:

Be it known that I, AUGUST GOERTZ, a citizen of the United States, residing at Newark, in the county of Essex and State of New Jersey, have invented certain new and useful Improvements in Purse-Frames; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The present invention, set forth in detail hereinafter, relates to improvements in purse or similar frames made up of pivotally-secured sections or plates adapted to be folded against each other in the manner of a system of arms or levers commonly known as "lazy-tongs;" and the object of the present invention is to secure a frame of great strength and one which is better adapted to be used on bags of this class.

The invention therefore consists in providing certain of said sections or plates comprising the lazy-tongs with prongs or points adapted to be forced through the material and bent down thereon, whereby a simple and cheap construction is the result.

In the accompanying sheet of drawings, Figure 1 is a side view of my improved purse-frame secured to the upper end of a bag of any suitable material, the frame being represented in its closed position. Fig. 2 is a front view of the frame when open, clearly illustrating the operation of the plates or sections of the frame when the purse has been opened. Fig. 3 is a top view of the frame, showing the pivoted plates or sections in their open relation to each other and provided with means formed integrally therewith on some of said plates or sections adapted to be forced through the material of the bag for securing the same to the frame. Figs. 4 and 5 are detail views of the frame-sections employed, and Fig. 6 is a vertical section of one of the plate or frame sections provided with the pointed prongs, illustrating the manner of forcing the same through the material and bending the prongs down upon the opposite

side of the material in order to secure the mouth of the bag to the frame.

Similar reference-letters are employed to indicate corresponding parts in each of the several views.

The purse or bag on which my improved frame is intended to be used is of the ordinary construction, and consists of an ordinary bag *a*, made of leather or any other suitable material.

As illustrated in the accompanying sheet of drawings, the mouth-closing device or frame to be secured to the bag consists, essentially, of the plates or sections *b* and *b'*, pivotally connected with each other at different points by means of pins, rivets, or screws *c*. These sections comprising the frame, when in their open relation, form two concentrically-arranged rings, as shown in Fig. 3, which are secured together by the pins, rivets, or screws *c*, and the inner ring, which is formed by the sections or plates *b'*, is provided with the inwardly-bent prongs or points *b*², as shown.

In Figs. 4 and 5 are shown the forms of the sections *b* and *b'*, which I contemplate using in the construction of my improved purse-frame. The frame-section *b*, as will be noticed from said Fig. 4, is provided with the plain or rounded ends and holes or perforations *b*³, substantially as shown, while the section *b'* is provided at its lower end with an integrally-formed prong or point *b*² and the holes or perforations *b*⁴. Any desirable number of such plates or sections *b* and *b'* are riveted together to form what is known as "lazy-tongs," the ends of which are also secured together, so as to form a circular frame *B*, provided at its lower side with the inwardly-projecting prongs or points *b*², as will be evident from the drawings. Now when it is intended to attach the bag *a* the upper rim *a'* of the same is forced upon the prongs *b*², which pass through the material, and are then firmly bent down upon the opposite side of the material, as clearly shown in Fig. 6.

As shown in Figs. 1, 2, and 3, the frame *B* is provided with a lid or cover *d* and a finger-piece *e*. When the frame-sections comprising the frame *B* have been closed upon each

- other, the lid or cover *d* can be forced down over the upper end of the frame-sections and the frame securely held in its closed position. It will be understood that any number of 5 such sections *b* and *b'* can be employed, according to the size of the frame desired, and the prongs *b*² need not necessarily be formed with the plates *b'*, for they can be riveted integral thereto by making the lower rivet in the 10 lazy-tongs long enough to pass through the two sections *b* and *b'*, and also through the thickness of metal of which the prong is made, which thus becomes secured upon the back of the section *b'*.
- 15 Having thus described my invention, what I claim is—
1. A purse-frame comprising therein a system of combined plates or sections *b* and *b'*, adapted to be spread and folded in the manner of lazy-tongs, said sections *b'* being pro- 20

vided with means formed integral therewith for attaching the material of the bag thereto, as and for the purposes set forth.

2. A purse-frame comprising therein a system of combined plates or sections *b* and *b'*, 25 adapted to be spread and folded in the manner of lazy-tongs, said sections *b'* being provided at their lower ends with prongs or points adapted to be forced through the material and bent over thereon for securing the bag to the frame, as and for the purposes set forth.

In testimony that I claim the invention set forth above I have hereunto set my hand this 16th day of February, 1891.

AUGUST GOERTZ.
